UNITED STATES PATENT OFFICE.

HENRY BARNES, OF NEW HAVEN, CONNECTICUT.

DESIGN FOR A LAUNDRY-WAGON.

SPECIFICATION forming part of Design No. 19,104, dated May 21, 1889.

Application filed April 27, 1889. Serial No. 308,875. Term of patent 14 years.

To all whom it may concern:

Be it known that I, HENRY BARNES, a citizen of the United States, residing at New Haven, in the county of New Haven and State of Connecticut, have invented certain new and useful Improvements in a Design for a Laundry-Wagon; and I do declare the following to be a full, clear, and exact description of the invention, such as will enable others skilled in the art to which it appertains to make and use the same, reference being had to the accompanying drawing, and to the letters and figures of reference marked thereon, which form a part of this specification.

This invention has relation to designs for laundry-wagons; and it consists in the novel design of the whole structure, as hereinafter fully described, and pointed out in the claim.

In the accompanying drawing is represented a design for a laundry-wagon, which consists

of the body A, representing a wash-boiler, the seat B, representing a wash-tub, and the dash C, representing a rubbing-board, all mounted on running-gear, as shown.

The side lamps, which are represented by sad-irons, are minor features, and are not absolutely essential to the general design.

What I claim as my design is—

The design for a laundry-wagon, consisting of the wash-boiler A, for the body, the wash-tub B, for the seat, and the rubbing-board C, for the dash, substantially as shown and described.

In testimony whereof I affix my signature in presence of two witnesses.

HENRY BARNES.
